UNITED STATES PATENT OFFICE.

ANTON POTOLSKY, OF ST. LOUIS, MISSOURI.

BAKER'S PEEL.

1,116,729.

Specification of Letters Patent. Patented Nov. 10, 1914.

Application filed February 13, 1914. Serial No. 318,498.

To all whom it may concern:

Be it known that I, ANTON POTOLSKY, citizen of the United States, residing at St. Louis, State of Missouri, have invented 5 certain new and useful Improvements in Bakers' Peels, of which the following is a full, clear, and exact description, reference being had to the accompanying drawings, forming a part hereof.

10 My invention has relation to improvements in bakers' peels; and it consists in the novel construction of peel more fully set forth in the specification and pointed out in the claims.

15 In the drawings, Figure 1 is a plan of my improved peel, parts being broken away; Fig. 2 is a side edge view thereof; Fig. 3 is a transverse section on the line 3—3 of Fig. 1; Fig. 4 is a longitudinal sectional detail on the line 4—4 of Fig. 1; and Fig. 5 is an enlarged cross-sectional detail on the line 5—5 of Fig. 1.

20 The object of my invention is to construct a baker's peel which will not warp under the heat to which it is usually subjected; one which is durable and will last a maximum length of time; one which when worn may be readily removed from its handle and a new peel substituted; one provided with 25 improved means of locking the handle to the peel; and one possessing further and other advantages better apparent from a detailed description of the invention which is as follows:

30 Referring to the drawings, 1, represents the body portion of the peel, the same being provided at its rear edge in a transverse groove *a*, said groove receiving the basal tongues *b* of the inner terminal stiffeners or 35 corner pieces 2, the inner ends or sides of said stiffeners being provided with tongues *c* which enter corresponding grooves *d* formed in the adjacent faces of the guide-strips 3, 3, said strips being extended a suitable distance beyond the stiffeners 2, 2 and serving as guides for the handle of the peel. The bases of the strips 3 terminate in 40 tongues *b'* which are likewise received by the transverse groove *a* of the member 1, the inner faces of the strips 3 being preferably concaved, and receiving between them the basal terminal of the handle having correspondingly convexed sides or faces engaging the concaved faces of the strips 3. The 45 base of the handle terminates in a tongue *b''* which freely enters the groove *a*, the handle

being locked to the strips 3 by means of a screw-bolt 5 passed transversely therethrough and through the strips 3, one end of the bolt carrying a securing nut *n*, and the other being provided with a swinging handle or link 6 which, after the parts are secured, is swung into a longitudinal groove *h* formed for its reception in the outer face of one of the strips 3. The link 6 is flat and only partially enters the groove *h*, the portion projecting out of the groove being in position to be readily seized between the thumb and forefinger. To remove the handle, the nut *n* is first unscrewed, after which the link 6 is swung out of its groove *h*, (dotted position Fig. 1) and, by means of said link the bolt is withdrawn, thus releasing the handle 4, whereupon the latter may be pulled out of the member 1 and out from 50 between the strips 3, 3 and attached to a new peel.

55 The grain of the main body of the peel or member 1 is in the direction of its length, or parallel to the length of the handle 4, whereas the grain of the stiffeners 2 is at right angles thereto or across the member 1. Since wood warps in lines parallel to the grain, it follows that the pieces 2 will arrest any tendency on the part of the peel 1 60 to warp, thus preserving the desired flatness in the peel. Preferably, the stiffeners 2, 2 are formed of oak, the member 1 being of poplar, though I do not wish to be restricted to any particular kind of wood or 65 material entering into the construction of the peel. Again, while it is preferable to form the grooves in the members 1 and 3, and the tongues in the members 2, 2, a reversal of this arrangement would not be a 70 departure from the nature and spirit of my invention. With the exception of the removable handle 4, the several parts are united together with glue or similar adhesive 75 into which the tongues *b*, *b'*, *c*, are dipped before insertion into their respective grooves, as well understood in the art. The 80 peel proper is reinforced and stiffened by transverse dowels or bars 7 as shown.

Having described my invention what I 85 claim is:—

90 1. A baker's peel comprising a body member or peel proper, stiffener members at the opposite corners of the inner terminal thereof secured thereto by a tongue and groove 95 connection, strips coupled to the inner adjacent terminals of the stiffeners and to the 100

- body member and extending beyond the stiffeners, a handle inserted between said strips and engaging the body member, and means for locking the handle to said strips.
- 5 2. A baker's peel comprising a body member or peel proper, stiffener members at the opposite corners of the inner terminal thereof secured thereto by a tongue and groove connection, guide strips secured by tongue and groove connections to the inner adjacent ends of the stiffeners and to the adjacent end of the body member, said strips being spaced apart, a handle inserted between the guide strips and engaging the 15 body member by a tongue and groove connection, the strips being extended beyond the stiffener members, and a bolt passed transversely through the extensions and through the handle for locking the latter to the strips.
3. A baker's peel comprising a body member or peel proper, stiffener corner pieces at the inner terminal of said body member, guide-strips disposed at the inner adjacent 25 ends of the corner pieces and secured thereto and to the body member and spaced apart and extending beyond the corner pieces, a handle inserted between the strips, a securing bolt passed transversely through the strips and through the handle, a terminal link hinged to one end of the bolt, the outer 30 face of one of the guide strips being provided with a groove or recess for receiving the link when out of commission.
- 35 4. A baker's peel comprising a body member or peel proper provided with a transverse groove at its inner terminal, corner
- pieces provided with tongues received by said groove, the inner adjacent ends of the corner pieces being provided with tongues, 40 guide strips disposed between the corner pieces and spaced apart and extending beyond the corner pieces, the outer faces of the strips having grooves for receiving the tongues formed at the inner adjacent ends of the corner pieces, and provided with basal tongues entering the transverse terminal groove of the body member, a handle inserted between the guide strips and terminating in a basal tongue removably received by the 45 transverse groove of the body member, a securing bolt passed transversely through the guide strips and handle, a link hinged to one end of the bolt, the outer face of one of the 50 guide strips being recessed to receive the link when the latter is out of commission, the grain of the corner pieces being transverse to the direction of the grain of the body member, and transverse to the general 55 direction of the handle.
- 60 5. A peel comprising a body portion having the grain of the wood disposed in one direction, a handle leading centrally from the body portion, and corner pieces secured to the body portion on opposite sides of the handle, the grain of the corner pieces being transverse to the direction of the grain in the body of the peel.

In testimony whereof I affix my signature, in presence of two witnesses.

ANTON POTOLSKY.
